UNITED STATES PATENT OFFICE.

EDWARD A. INGRAHAM, OF NORTH SYDNEY, NOVA SCOTIA, CANADA.

CIGAR-HOLDER.

No. 917,948.

Specification of Letters Patent.

Patented April 13, 1909.

Application filed August 14, 1908. Serial No. 448,576.

To all whom it may concern:

Be it known that I, EDWARD A. INGRAHAM, residing at North Sydney, in the Province of Nova Scotia and Dominion of Canada, have invented a new and useful Cigar-Holder, of which the following is a specification.

This invention relates to that class of devices especially designed for attachment to 10 cigars, to prevent the ashes, and fire from being accidentally knocked off of the cigar, and scattered.

The invention has for its object to provide 15 an ash protector of this character adapted to cover and protect the lighted end of a cigar, and by means of which the ash and sparks are prevented from dropping off the end of the same so that the cigar can be safely smoked in places where there would 20 be danger in dropping a spark from a cigar.

The invention further has for its object 25 to provide a cigar ash protector by means of which a cigar will burn evenly, and last longer.

The invention further has for its object 30 to provide a cigar ash protector which can easily be attached to and detached from a cigar, which can be adjusted on the cigar as it burns shorter, which can be used with or without a cigar holder; and which is simple in construction, light and portable, and inexpensive to manufacture.

The invention consists of a cigar ash protector, constructed and arranged as herein- 35 after set forth and claimed.

Referring to the accompanying drawings: Figure 1, is a perspective view of the invention showing it in position for use. Fig. 2, is a side view of the invention in folded 40 position. Fig. 3 is a modification of the invention. Fig. 4 is another modification of the invention. Fig. 5 is a detail longitudinal sectional view of a portion of a cigar holder showing a perforating attachment in 45 connection therewith. Fig. 6 is a similar view showing a modified form of perforating attachment.

The invention comprises a cap or casing 1, of suitable shape to fit over the lighted end 50 of a cigar, and as here shown is in the shape of a thimble, formed of wire gauze, or perforated material, which is non combustible and serves as a screen. The cap 1, is preferably provided at its open end with a rim 2 of metal or other suitable material, to reinforce the wire gauze, and of a proper

diameter to fit over a cigar 3, as shown in dotted lines in Fig. 1 of drawing.

In order to retain the cap 1 on the cigar, and also to hold it in adjusted position 60 thereon, a suitable device is provided therefor and as here shown, consists of an arm 4, pivoted at one end to the rim 2, and having mounted on its other end a suitable clutch 5, adapted to clamp a cigar. The 65 clutch 5, is formed of two curved arms 6, adapted to fit over and clamp a cigar as shown in Fig. 1, said arms 6, being each formed with a flattened portion 7, through which the arm 4 projects and terminates in 70 a head 8 to keep the arms 6 on the arm 4. The arms 6, are each formed with a handle 9, said handles extending in opposite directions to each other. The arms 6 are adapted to open and close toward each other, their 75 flattened portion 7, turning on the arm 4, the arms 6, being operated by the handles 9. To hold the arms 6 in clamped position on a cigar, a coiled spring 10 is mounted on the arm 4, and connected with the arms 6 80 adjacent to their pivoted connection with arm 4, said spring by its tension acting to draw the arms 6 toward each other when they are expanded. The handles 9 not only serve to operate the arms 6, but may also serve as 85 a holding support for the hand to hold the cigar. As the cigar burns shorter the cap or casing 1, is moved over the burning end of the cigar by unclamping and adjusting the arms 6.

In use the ashes of the cigar may be knocked off without removing the cap from the cigar, the ashes sift through the cap. When not in use the arm 4 is folded up on the casing 1, and may be carried in a suitable receptacle.

The adjustable clutch 5, adapts the device to be used with cigars of different size, and it may be made of a size and shape to adapt it for cigarettes.

In the modification shown in Fig. 3, the arm 4 is dispensed with and a thimble 11 of gauze or perforated material is provided with a metal rim 12 having the circumferential slots 13. Pivoted to a lip or projection 14 on the rim 12 is a clutch 15 consisting of two curved arms 16 pivoted on a pin 17 in the lip 14 and each having a curved lateral operating handle 18. A coiled spring 19 mounted on the pivot pin 17, and 110 engaging the arms 16 acts upon the latter to draw them together and clamp a cigar on

which the thimble 11 is mounted. As shown in Fig. 3 the arms 16 are adapted to swing through the slots 13 in adjusting the clutch to a cigar.

5 In the modification in Fig. 4 a thimble 20 of gauze or perforated material has a metal rim 21 with a projection 22 depending therefrom on which is mounted a clutch 23, consisting of curved arms 24 pivoted on a pin 10 25 on the projection 22 and having lateral operating arms 26. A coiled spring 27 on the pivot pin 25 and engaging the arms 26 acts upon the latter to draw them together and clamp a cigar on which the thimble 20 15 is mounted.

If desired the holders shown in Figs. 1 and 4 of the drawing may each be provided with a spur or needle 28 for perforating the end of the cigar so as to permit the same to 20 draw freely, and in some cases one side of the holder may be provided with a knife 29 for cutting or slitting the cigar when the latter is introduced within the holder, as best illustrated in Fig. 6 of the drawing.

25 It will of course be understood that when using the perforating attachment the cap or holder will be first positioned on the reduced end of the cigar and then removed and placed on the lighted end thereof, in the 30 manner before described.

Having described the invention, I claim:

1. A cigar ash protector, consisting of a foraminous cap, adapted to fit over the lighted end of a cigar, and a cigar clamping device spaced from and pivotally connected with the cap, said clamping device being 35 foldable laterally on the outside of the cap.

2. A cigar ash protector, consisting of a screen cap, adapted to fit over the lighted

end of a cigar, an arm projecting lengthwise from and pivotally mounted on said cap, and spring actuated clamping members, hinged on said arm and adapted to clamp a cigar.

3. A cigar ash protector, consisting of a foraminous cap, adapted to fit over the lighted end of a cigar, and having a reinforcing band around one end thereof, an arm hinged to said band, and a pair of spring actuated clamping members hinged to said arm, and adapted to clamp a cigar.

4. A cigar ash protector, consisting of a screen cap, adapted to fit over the lighted end of a cigar, an arm extending lengthwise from said cap and hinged thereto, a clamping member, mounted on the end of said arm and adapted to engage the cigar, said clamping member and arm being folded against the screen cap.

5. A cigar ash protector including a foraminous cap adapted to fit over the lighted end of a cigar, a clamping device carried by the cap, and a perforating attachment disposed within said cap.

6. A cigar ash protector including a conical foraminous cap adapted to fit over the lighted end of a cigar, a clamping attachment carried by the large end of the cap and adapted to embrace the cigar, and a perforating attachment disposed at the reduced end of the cap and housed within the latter.

In testimony that I claim the foregoing as my own, I have hereto affixed my signature in the presence of two witnesses.

EDWARD A. INGRAHAM.
